DUMP TRUCK FOR TRASH

Gordon L. Stith, 970 Leadora Ave., Glendora, Calif.

Filed June 26, 1963, Ser. No. 75,524

Term of patent 14 years

(Cl. D14—3)

FIG. 1

I claim:

The ornamental design for a dump truck for trash,
as shown.
